[57] CLAIM

The ornamental design for a motorcycle foot peg, as shown and described.

DESCRIPTION

FIG. 1 is a top plan view of a motorcycle foot peg illustrating my new design, the two rectangular sections with parallel lines represent rubber inlays with corrugated surfaces; FIG. 2 is a side elevational view thereof, the opposite side being a mirror image thereof;

FIG. 3 is a rear view thereof;

FIG. 4 is a right end view thereof;

FIG. 5 is a left end view thereof; and,

FIG. 6 is a perspective view thereof.
